UNITED STATES PATENT OFFICE.

CHARLES M. MORRISON, OF PHILADELPHIA, PENNSYLVANIA, ASSIGNOR TO THEODORE HEDINGER, JR., OF PHILADELPHIA, PENNSYLVANIA.

SHEET-GAGE FOR PRESSES.

No. 903,751.

Specification of Letters Patent.

Patented Nov. 10, 1908.

Application filed April 2, 1908. Serial No. 424,717.

To all whom it may concern:

Be it known that I, CHARLES M. MORRISON, a citizen of the United States, residing at Philadelphia, in the county of Philadelphia and State of Pennsylvania, have invented new and useful Improvements in a Sheet-Gage for Presses, of which the following is a specification.

My present invention relates to improvements in paper-positioning devices for printing-presses of the platen type, and it has for its object primarily to provide an improved device of this kind wherein the sheets are engaged both on a horizontal and a vertical edge by stops which are simultaneously movable toward the sheet and in different angular paths, causing a resultant motion of the sheet in a diagonal direction whereby the sheet will be positioned precisely both vertically and laterally.

Another object of the invention is to provide improved means for actuating the sheet-engaging stops, the gages being preferably actuated automatically during the movements of the platen by means of an operative connection with the pivoted bar or other part of the gripper mechanism.

Another object of the invention is to provide a sheet-positioning device of this character comprising vertically and laterally movable stops, one of the said stops being provided with means for positively actuating the other stop in one direction, and automatic means being provided for effecting a return movement of the latter stop.

Further objects of the invention are to provide novel tensioning devices for stretching a strip which extends across the face of the platen and carries one or more paper-engaging stops, the latter stops being provided with novel devices for frictionally holding them in different adjusted positions longitudinally of the strip, and also to provide improved means for mounting the lateral stop and for securing this stop in different adjusted positions.

To these and other ends, the invention consists in certain improvements, and combinations and arrangements of parts, all as will be hereinafter more fully described, the novel features being pointed out particularly in the claims at the end of the specification.

In the accompanying drawing: Figure 1 is a plan view of a press platen equipped

with a paper-gage constructed in accordance with my present invention, the platen and grippers being shown in open position, and the sheet being shown in position previous to its positioning by the stops; Fig. 2 is a view similar to Fig. 1, the sheet being shown positioned by the movable stops; Fig. 3 represents an edge view of a portion of the platen and the gage fitted thereon, the parts being shown in printing position; Fig. 4 represents a longitudinal section on the line 4-4 of Fig. 2; Figs. 5 and 6 represent transverse sections on the lines 5-5 and 6-6 respectively, of Fig. 4; Fig. 7 is a perspective view of one of the slides which carries the vertically movable stops; Fig. 8 is a perspective view of one of the tensioning and supporting devices for the strip which carries the vertically movable stops; Fig. 9 represents a fragmentary sectional view on the line 9-9 of Fig. 5; Fig. 10 is a perspective view of a cam for actuating one of the slides which carries the vertically movable stops; Fig. 11 is a perspective view of one of the supporting brackets for attaching the gage to the press platen; and Fig. 12 is a detail view of one of the vertically movable stops.

Similar parts are designated by the same reference characters in the several views.

Paper-positioning devices constructed in accordance with my present invention are capable of being applied generally to presses of various types, and in so applying the invention, it will be understood of course that certain changes or modifications may be made according to the different applications of the invention.

In the present instance, I have shown the invention as applied to a press platen and gripper mechanism of a well known construction, the gage being so applied thereto as not to require a material modification of such parts, so that the gage may be readily applied to such presses in common use with the greatest facility. It is to be understood, however, that the particular form of gage shown, in the present instance represents merely one embodiment of my invention and that I do not wish to be restricted to the exact constructions shown.

In the present instance, the platen 1 is of a usual construction having the tympan-bails or clamps 2 and 3 arranged at the upper and lower edges thereof. At the lower edge of the platen is mounted the usual piv-

oted gripper bar 4 carrying the upwardly extending grippers 5 which are brought into engagement with the face of the sheet to hold the latter against the platen after the sheet has been properly positioned by the gages, and these grippers disengage from the sheet as the platen swings into open position in order to permit removal of the printed sheet and the substitution of a fresh one, such mechanism being used on presses now in common use. The gripper bar is provided with journals 6 at its opposite ends which usually engage brackets fastened on the platen, but in order to readily adapt the invention to existing presses of this type, I have provided a pair of brackets 7 which have a horizontally extending arm 8 which is bolted or riveted to the back of the platen adjacent to its lower edge and an upwardly extending arm 9 of the bracket projects laterally beyond the vertical edge of the platen and serves to support the paper-positioning stops, an apertured lug 10 being provided on the bracket to form a bearing for the respective journal of the pivoted gripper bar. As I have previously stated, however, the bracket just described is provided as a convenient means for supporting the paper engaging stops and the gripper bar, and it is to be understood that any suitable means may be provided to support the stops. The gripper bar has a depending arm 11 carrying a roller or projection 12 which co-operates with the usual cam or other mechanism for moving the grippers to and from operative position relatively to the sheet carried by the platen.

The paper-positioning devices employed in the present instance comprise vertically and horizontally movable stops, the vertically movable stops being actuated by means of a pair of vertically movable slides 13, those shown in the present instance being substantially rectangular in cross section and guided to operate within a channel-shaped guide 15 bolted or otherwise secured to the arm 9 of the supporting bracket. Relative disengagement between the slide and its co-operating guide is prevented by means of a key 16 extending through and fastened to the vertical sides of the slide and a similar key 17 secured to and extending transversely of the guide, the keys operating respectively in longitudinal slots 18 and 19 formed respectively in the sides of the slide and guide. A tension spring 20 has its opposite ends connected to the respective keys and thereby serves to actuate the slide in one direction.

The paper-engaging stops 21 are mounted on a strip 22 which extends horizontally across the face of the platen, this strip being preferably of thin steel or other flexible material in order not to interfere with the operation of the grippers, and it is supported at its opposite ends by means of a pair of

supporting devices which are attached to and adjustable vertically on the respective slides. One of the said devices in the present instance is composed of a spring actuated carrier 23, the carrier having depending flanges 24 on its longitudinal edges to slidably engage a cross-head 25, the latter having vertical flanges 26 which overlap the longitudinal edges of the slide 13 and permit adjustment of the cross-head longitudinally thereof. The cross-head 25 carries a pin 27 which extends through an aperture 28 formed in a depending flange on the outer edge of the carrier 23, and the pin is surrounded by a helical compression spring 29, the ends of which bear respectively against the cross-head and carrier and therefore tend to move the carrier outwardly. The opposite ends of the strip 22 are connected to the respective carriers at the opposite sides of the platen, the strip in the present instance being provided at its opposite ends with apertures 30 which detachably engage hook-shaped projections 31 formed on the inner edges of the respective carriers 23, the spring 29 normally operating one of the carriers to tension the strip and retain it in co-operative relation with the respective hooked projections. By pressing inwardly on the outer edge of one of the carriers 23, the tension of the respective spring may be overcome and the strip may be disengaged and removed from its co-operating projections, and any suitable number of these projections may be provided for supporting the strip, a pair of such projections being shown in the present instance on each carrier, these projections being spaced vertically in order to permit an interchanging of the strip therewith.

In order to accommodate sheets of different vertical dimensions, the strip-carrying devices, as previously stated, are adjustable vertically on the respective slides, the latter in the present instance being each provided with a longitudinal slot 32 within which operates a bolt 33, the upper threaded end of this bolt extending through an aperture 34 in the cross-head and through a longitudinally elongated slot 35 in the carrier 23, and a nut 36 is fitted on this bolt for the purpose of clamping the strip-supporting device in fixed relation to the slide 13. It is generally preferable to clamp the cross-head to the slide so as to prevent vertical shifting thereof, but to leave the carrier 23 free to operate in order to permit detachment of the strip, and for this purpose, the lower end of the nut is provided with a reduced shoulder 37 which extends loosely through the slot 35 and bears upon the upper side of the cross-head so that the carrier 23 is free to slide beneath the nut. The opposite strip carrier 23 may be stationary.

The sheet-engaging stops 21, as previously stated, are adjustable longitudinally of the

strip 22, and in the present instance they are provided with openings 38 to slidably engage the strip and openings 39 which extend at a right angle to the opening 38 and receive a resilient strip or spring 40 which has a yielding bearing on the strip to produce sufficient friction to hold the stop in the desired adjusted position, and the upper end of the strip may be turned outwardly slightly to facilitate the entrance of the edge of the sheet beneath it.

The vertically movable slides, as previously stated, may be actuated to carry the stops 21 into engagement with the edge of the sheet by any suitable means, but in the present instance, it is preferable to actuate these slides automatically by means of the gripper mechanism, the pivoted bar 4 of the latter being provided with a cam, crank or other suitable device, a pair of cams 41 being used in the present instance which are rotatable with the gripper bar and each has an inclined portion 42 which co-operates with a projection 43 on each slide to move the gages before the grippers engage the sheet and a concentric portion 42a which engages said projection but does not move the gage while the grippers are engaging the sheet, the cams overcoming the action of the springs 20 of the slides and serving to move the latter upwardly while the grippers approach, but before they engage the sheet on the platen, and after these grippers recede from the sheet, the springs 20 will serve to automatically return the slides to their lower positions.

The cams 41 in the present instance are formed separately from the gripper bar and comprise apertured disk sections which fit over the journals 6 of the gripper bar and are provided with laterally turned flanges to present a relatively wide wearing surface for the projections on the slides. The disk portions of the cams are provided each with an arm 44 having a pair of oppositely arranged laterally turned projections 45 which embrace the respective ends of the gripper bar and thus cause the cams to rotate therewith. By forming the cams separately from the gripper bar and operatively connecting them therewith in the manner just described, gripper bars of the ordinary construction may be used, but in some cases, the cam may be formed integrally or as a part of the gripper bar as will be obvious.

A lateral gage 46 is provided to co-operate with a vertical edge of the sheet, this lateral gage being arranged to operate in a path at right angles to the direction of movement of the stops 21. In the present instance, this lateral gage comprises a strip or shank carrying a stop 47 at the inner end thereof, the shank being fitted to rest in a seat 48 having an undercut flange 49 at one edge and a pointed screw 50 fitted

opposite to said flange, the screw bearing upon the upper corner of the shank or strip and thereby securing it in adjusted position and preventing disengagement thereof from its seat. This seat is mounted on a carrier 51, and the latter rests upon the upper end of the arm 9 of the bracket and is provided with a pair of longitudinally extending guide pins 52, the latter extending through corresponding openings in an abutment 53 secured to the bracket, and a helical compression spring 54 encircles one of these pins and bears at its opposite ends against the abutment and an end of the carrier 51, the spring acting normally to move the lateral stop outwardly or to retract it from the sheet. Lateral gages having shanks of different lengths may be used as desired.

During the vertical movement of the stops 21, a corresponding horizontal inward movement is imparted to the lateral stop 47, and any suitable means may be employed for effecting the movement of the latter stop. In the present instance, the carrier 51 for the lateral stop is provided with a roller or projection 55, and the abutment 53 is provided with a corresponding roller or projection 56 which is arranged at the outer side of the roller first mentioned. A wedge 57 is attached to the slide 13 and provided with a cam or incline 58 at one side thereof, the inter-position of the wedge between the rollers as the slide 13 moves upwardly causing the rollers or projections to separate and thus move the carrier for the lateral stop 100 inwardly against the vertical edge of the sheet. A return motion of the slide will retract the wedge from its position between the rollers and thereby permit the spring 54 to retract the carrier. The wedge 57 in 105 the present instance is pivoted to the upper end of one of the slides 13 in order to permit it to swing freely as it enters between the rollers.

In operating a press provided with a paper-gage constructed in accordance with the present embodiment of my invention, the vertically movable stops 21 may be shifted to the proper positions along the strip 22 and the latter may be adjusted at the proper height on the platen by loosening the nuts 36 and subsequently tightening them. The lateral stop 47 may also be adjusted inwardly or outwardly according to the width of the sheet by loosening the screw 50 and shifting the shank of this stop in its seat. The gripper mechanism, it is assumed, is the same as that used on many presses now in use, the roller 12 co-operating with a cam or other suitable device for moving the grippers into engagement with the sheet on the platen as the latter swings into printing position, and retracting the grippers as the platen moves from printing position. While the platen is in open position as shown in

Fig. 1, the grippers will be separated from the sheet so as to permit a printed sheet to be removed and a fresh sheet to be substituted. While the grippers are in the position just mentioned, the projection 43 on each slide will rest at the base of the inclined portion of the cams so that the slides will be held in lowermost position under the resilient action of the springs 20, and the 5 wedge 57 will be withdrawn from a position between the rollers 55 and 56, the spring 54 yieldingly retaining the lateral stop in its outermost position. As the platen moves toward printing position, the grippers will 10 move toward the sheet, and the rotation of the gripper bar will operate the cams so as to lift the slides and consequently the vertically movable stops 21 supported thereon. This upward movement of the slides also 15 causes the wedge 57 connected to one of them to enter between the projections 55 and 56, these projections being thus separated and causing an inward movement of the lateral stop 47. In feeding the sheets rapidly to the 20 press, it often happens that the horizontal or vertical edge of the sheet does not rest closely against the stops, but as the lower stops in the present instance move upwardly and the lateral stop moves inwardly, the stops are 25 brought against the corresponding edges of the sheet with certainty, and the resultant diagonal movement of the sheet serves to carry the latter precisely into printing position. As the platen is retracted, the projections 30 on the vertically movable slides traverse the inclined portions of the cams, and under the action of the springs 20, these slides are retracted or moved automatically toward their lowermost positions. At the 35 same time the slides are retracted, the wedge 57 will also be withdrawn from a position between the rollers or projections 55 and 56, and the carrier which actuates the lateral stop is automatically retracted under the action of the spring 54.

Sheet-positioning gages constructed in accordance with my present invention are comparatively simple in construction and in practice they operate with certainty to insure an accurate registration or positioning of the sheets. By actuating the stops automatically by means of the gripper mechanism, the construction of the device is materially simplified and correct operation is insured, and by providing stops which are retracted automatically by means of springs, an even movement is imparted to the stops, and wearing of the parts cannot impair the operation thereof.

The present invention also provides many features of improvement over paper-gages of the character covered by my prior patent, No. 843,688 granted February 12, 1907.

I claim as my invention:—

60 1. The combination with a press platen

and a rotatable gripper bar mounted thereon, of a lateral stop guided to move toward and from a lateral edge of a sheet on said platen, a second stop operable positively by the gripper bar to engage a different edge of a sheet, and means embodying a wedge operable by the said second stop for actuating the lateral stop positively to position the sheet.

2. The combination with a press platen of a pair of stops guided to move toward and from the sheet in different angular paths, a reciprocatory wedge actuated directly by one of the stops for moving the other stop in one direction only and means for effecting a reverse movement of the latter stop.

3. The combination with a press platen, and a rotatable bar journaled thereon, of a stop movable toward and from an edge of a sheet on the platen in a plane parallel to the face of the latter, a second stop movable into engagement with a different edge of the sheet and a cam rotatable with said bar for moving both of said stops toward the respective edges of the sheet.

4. The combination with a press platen, and a rotatable bar journaled thereon, of a stop guided to move toward and from an edge of a sheet on the platen, means on said bar for positively moving the stop into engagement with the sheet, a second stop operable directly by the stop first mentioned and adapted to engage a different edge of the sheet and a spring acting independently of said bar for retracting the stop first mentioned.

5. The combination with a press platen, and a rotatable gripper bar journaled thereon, of a lateral stop guided to move horizontally toward and from a lateral edge of a sheet on the platen, a reciprocatory wedge for positively moving the stop into engagement with the sheet, and a spring acting to retract the stop and to retain the latter in cooperative relation with the wedge.

6. The combination with a press platen, and a rotatable bar journaled thereon, of a pair of slides guided to operate vertically at opposite sides of the platen, a strip connecting said slides and extending across the face of the platen, said strip carrying a stop movable toward and from an edge of a sheet on the platen, a pair of cams rotatable with said bar and co-operating with the slides to actuate the latter positively to move said stop in engagement with the sheet, and springs mounted independently of the bar and co-operating with said slides for retracting the stop.

7. The combination with a press platen, and a rotatable gripper bar journaled thereon, of a pair of slides guided to move vertically at the opposite sides of the platen, a strip detachably connected to said slides and carrying a stop which is movable toward and

from an edge of a sheet, means rotatable with the gripper bar and coöperating with said slides to positively move the stop into engagement with the sheet, and springs connected to the respective slides for retracting the latter.

8. The combination with a press platen, and a rotatable gripper bar journaled thereon, of a pair of slides guided to operate in parallel relation at opposite edges of the platen, a flexible strip extending across the face of the platen between said slides and carrying a stop adapted to move toward and from an edge of a sheet on the platen, a pair of cams rotatable with the gripper bar and coöperating with the slides to actuate the latter and move the stop positively into engagement with the sheet, and springs acting on the respective slides to retract the sheet-engaging stop.

9. The combination with a press platen, and a rotatable gripper bar journaled at the lower edge thereof, of a pair of slides guided to operate in parallel relation at the opposite vertical edges of the platen and carrying a stop which is movable toward and from an edge of a sheet resting on the platen, a pair of cams formed separately from and having projections detachably interlocked with the gripper bar so as to rotate the cams with the gripper bar, said cams coöperating with the slides to actuate the latter in one direction only, and springs acting on the respective slides to effect movement thereof in a reverse direction.

10. The combination with a press platen, of sheet-engaging stops movable toward and from the sheet in different angular paths, spring means acting to retract both of the stops, and means carried by one of the stops and movable transversely of the path of motion of the other stop for effecting a movement of the latter toward the sheet in its respective angular path, the stops being capable of independent relative movement.

11. The combination with a press platen, of a pair of slides guided to operate in parallel relation at opposite edges of the platen and carrying a sheet-engaging stop, a lateral stop guided to move toward and from the sheet in a path transverse to the direction of movement of the stop first mentioned, and a cam device actuated by one of said slides for moving the lateral stop positively in one direction.

12. The combination with a press platen, of a pair of slides guided to operate in parallel paths at opposite edges of the platen and carrying a stop to engage a lower edge of a sheet, a lateral stop movable toward and from a vertical edge of the sheet in a path transverse to the path of movement of the stop first mentioned, a cam device carried by one of said slides and coöperating with the lat-

eral stop to move it positively into engagement with the sheet, and a spring for effecting a reverse movement of the lateral stop during the retraction of the cam device.

13. The combination with a press platen, of a slide guided to operate at one edge thereof and carrying a sheet-engaging stop, a lateral stop movable toward and from the sheet in a path transverse to the direction of movement of said slide, the lateral stop having a roller or projection movable therewith, and a second projection being mounted in fixed relation, and a wedge device pivoted on said slide and having a portion adapted to enter between said projections to cause a movement of the lateral stop toward the sheet.

14. The combination with a press platen, of a strip adapted to extend across the face thereof and having means to engage and position a sheet thereon, and devices arranged at the opposite edges of the platen and coöperating with the ends of said strip, and a spring coöperating with one of said devices to tension the said strip.

15. The combination with a press platen, of a strip adapted to extend across the face thereof and having means to engage and position a sheet, devices mounted at opposite edges of the platen and having means to detachably engage the respective ends of said strip, one of said devices being movable in a direction longitudinally of the strip, and a spring acting on said movable device to tension the strip and prevent detachment thereof from the respective devices.

16. The combination with a press platen, of a strip having means to engage and position a sheet thereon, devices mounted at opposite edges of the platen for supporting said strip, the strip and supporting devices being detachably connected by hooks engaging apertures, and one of said devices being movable in a direction longitudinally of the strip, and a spring acting on said movable device to tension the strip and retain the hook-shaped projections in engagement with the respective apertures.

17. The combination with a press platen, of a slide guided to operate at one edge thereof and provided with a longitudinal slot, a cross-head adjustable longitudinally of the guide, a strip extending across the face of the platen and having sheet-engaging means thereon, a device for fastening said strip at one edge of the platen, a carrier engaging the opposite end of said strip and movable on said cross-head in a direction longitudinally of the strip, said carrier being provided with an elongated aperture, a spring interposed between said carrier and cross-head for operating the carrier to tension said strip, a bolt extending through the longitudinal slot in the slide and through the elongated aper-

ture in said carrier, a clamping device coöperating with the bolt and having a reduced part which extends through the elongated aperture in the carrier and bears on the cross-head to clamp the latter in different positions longitudinally of the slide, and means for reciprocating the latter to carry the strip toward or from the sheet.

18. The combination with a press platen, 10 of a strip extending across the face of the platen, and one or more paper-engaging stops mounted on said strip, each stop having a slot to slidably receive said strip and having a second slot extending transverse to 15 the length of the strip and having an upper wall extending continuously from one edge of the stop to the other, and a spring inserted in said second slot and having its upper end adapted to coöperate with the sheet, said 20 spring being confined closely within its slot and having a frictional engagement with the strip the continuous upper wall of the

slot containing said spring serving to prevent the latter from bending away from the strip.

19. A paper-gage or stop for press platens 25 comprising a stop having an elongated shank, a seat having an undercut flange at one side to coöperate with one edge of said shank and open at its opposite side to permit lateral detachment of the said shank, 30 and a screw mounted opposite to said flange at the open side of said seat and provided with a pointed or beveled end arranged to engage the upper corner of the opposite edge of said shank to lock the latter in different 35 longitudinal positions and prevent displacement thereof.

In testimony whereof I have hereunto set my hand in presence of two subscribing witnesses.

CHARLES M. MORRISON.
